PROCESS FOR TRANSFERRING PICTURES

Sarah A. Boyle and Robert J. Boyle, Bristol,
Conn.No Drawing. Application July 9, 1930
Serial No. 466,881

4 Claims. (Cl. 41—33)

This invention relates broadly to the art of picture transposition and involves particularly a novel process for transposing a picture, as it appears on one base, to another base.

The invention is concerned, primarily, with a process designed for use in conjunction with comparatively inexpensive pictures, the originals of which may be destroyed, without an appreciable loss, when the picture is transferred from its original base to a fabric base. In accordance with this invention, such pictures as those appearing on magazine covers, and in other similar places, are intended to be transferred or transposed to various fabric bases, of which lamp shades are typical.

In view of the relative cheapness of the original subjects, and to the end of maintaining the cost of the ultimate product as low as possible so as to render the commercialization of the process practical, this invention has as an important object the provision of a process, as outlined above, which may be readily carried out without the need of expert operators and which is simple and inexpensive and involves the use of materials, the cost of which is within limits commensurate with the above thoughts.

A novel process, such as contemplated hereby, may be characterized as including, as an essential phase, a step or steps for actually transposing, in an orderly arrangement, the coloring material from the base of the original subject to the base of the finished product and, as a subsequent phase, a step or steps for bringing out and fixing the colors to provide the finished article.

Various detailed objects and advantages of the invention are associated with the provision of the several steps which are necessary for a full and complete practical process, as outlined above. These will in part become apparent and in part be hereinafter stated as the description of the invention proceeds. For a full and more complete understanding thereof, reference may be had to the following detailed description of a complete process as provided hereby.

For the picture to be transferred, the invention has in view a wide range of subjects which, of course, may be of various kinds, types and color schemes. It is desirable that the original subject be not of appreciable value because the process hereof leaves the original base a blank. Hence, pictures, such as colored ones printed on paper and similar to magazine covers, as well as the magazine covers themselves, are particularly intended to be availed of as providing the

original subject of this process. While the instant process would be effective to transfer the pictures to almost any base desired, the invention particularly has in mind a fabric base, such as silk, linen or any other closely woven fabric having the requisite durability. Preferably, the fabric should have a mesh from 60 to 100 per square inch. Fabrics of this type are susceptible of formation into various commercial articles, such as lamp shades, wall panels and the like, and, when they carry a picture which has been placed thereon by the instant process, constitute a novelty of some little value.

The first important step in carrying out the instant process is to apply to and impregnate the fabric, which is to constitute the base of the finished article, with an adhesive mass. This mass may be of any preferred composition which is effective to adhere to the fabric and to the coloring materials of the original subject so that the latter will remain with the mass rather than with the original base. By way of example, the mass may take the form of a thick viscose paste which may be used to advantage and which is of the following composition—a base of para rubber and additional substances in the form of rosin, zinc oxide, white wax and spermaceti.

Just when the adhesive mass is applied to the fabric is not important. It may be applied at the factory where either the fabric or the mass is manufactured, and the fabric, with the adhesive mass applied thereto, may be sold to the public in the combined form. Obviously, a person availing of this process could also apply the mass to the fabric, the one important feature being that the fabric have the mass applied thereto.

The next essential step of the present process lies in applying the original subject face down to the fabric with the picture coming in close intimate contact with the adhesive mass on the fabric. Naturally, the original subject is cut to the proper dimensions so as to fill out the fabric in accordance with the wishes of the user. The properties of the adhesive material cause a close intimate contact between the picture and the adhesive mass which is maintained sufficiently long for the coloring materials to become thoroughly affixed to the mass on the fabric. At this point, the fabric is stripped from the original base leaving the latter in a blank condition. It is evident that the original base might just as well be stripped from the fabric, but the durable and flexible nature of the latter renders the first described method the more desirable.

From this point, where the coloring materials

defining the picture on the original subject have been transposed to the fabric base, the process may be completed in any one of several methods, two of which are characteristically distinct and 5 which are herein described. The first of these methods consists of applying turpentine to the face of the fabric which has been in contact with the original subject and permitting the turpentine to dry. Linseed oil is then applied in the 10 same manner as the turpentine and permitted to dry. The same effects obtained by the applications of the turpentine and linseed oil may be obtained by the use of any well-known commercial filler. After the application of either the 15 turpentine and linseed oil or the filler, which is effective to bring out the coloring on the fabric, the latter is fixed by the application of a fixative. A fixative of any desired composition may be employed, although either one of two compositions 20 is preferably employed. The first of these consists of pure spirits of terebenthene with one-half of one percent. oil of mirbane added, and the second is what is a combined developing and fixing solution which consists of the mixture of 25 gum arabic and rosin which are suitably boiled and thinned out to a desired consistency with pure turpentine. By proceeding in accordance with the method described, the fabric with the picture thereon is rendered translucent and trans- 30 parent.

The application of the fixative to the fabric fixes the colors so as to provide a permanent finished product. If the fabric is not of a desired thickness, it may be stiffened by one or more 35 applications of balloon dope and, when this step is included in the process, it constitutes the final step thereof.

In choosing a fabric for the base of the finished 40 article, any color for the base may be chosen which will blend with the picture of the original subject. This feature is of importance because it will enable the person availing of the process to obtain a different appearance effect from that provided by the picture as it appears on the original base. Also, when it is desired to obtain richer 45 tone effects, poppy oil may be used in place of the linseed oil which is employed to bring out the coloring.

It is evident that the carrying out of the foregoing 50 process does not necessarily involve the use of a skilled operator, nor are the materials essential to the process particularly expensive. The fact is everything associated with the process lends to a finished product of relatively small cost, and the essential simplicity of the process insures of its being properly carried out without liability of mistake or marring of the finished 55 transposed picture. The feature of transferring the picture to a fabric base is of importance because a fabric is essentially flexible and is susceptible of being formed into various commercial articles such as lamp shades and the like.

While a preferred specific embodiment of the 60 invention is hereinbefore set forth, it is to be un-

derstood that the invention is not to be limited in connection with the specific steps and materials described, as various modifications of these details may be provided in putting the invention into practice within the purview of the appended 80 claims.

We claim as our invention:

1. A process for transposing a picture from an 85 original subject to a fabric base, which consists in first impregnating the fabric with an adhesive mass having a base of para rubber and additional constituents in the form of rosin, zinc oxide, white wax and spermaceti, causing a close intimate contact between the picture on the original subject and the fabric, then stripping the fabric from the original subject, applying materials to bring out the coloring on the fabric, and then applying a fixative to fix the coloring on the fabric.

2. A process for transposing a picture from 90 an original subject to a fabric base, which consists in first impregnating the fabric with an adhesive mass having a base of para rubber and additional constituents in the form of rosin, zinc oxide, white wax and spermaceti, causing a close 95 intimate contact between the picture on the original subject and the fabric, then stripping the fabric from the original subject, applying materials to bring out the coloring on the fabric, and then applying a fixative which consists of 100 pure spirits of terebenthene and one-half of one percent. of oil of mirbane.

3. A process for transposing a picture from an 105 original subject to a fabric base, which consists in first impregnating the fabric with an adhesive 110 mass having a base of para rubber and additional constituents in the form of rosin, zinc oxide, white wax and spermaceti, causing a close intimate contact between the picture on the original subject and the fabric, then stripping the fabric 115 from the original subject, applying materials to bring out the coloring on the fabric, and then applying a fixative consisting of gum arabic, rosin and turpentine.

4. A process for transferring a picture directly 120 from the base of an original subject to a fabric base, which consists in applying an adhesive mass to the fabric base, causing an intimate contact 125 between the adhesive mass on the fabric and the picture of the original subject, the adhesive mass being of such a character that it will adhere to the fabric and to the coloring materials of the original subject so that the latter will remain with the mass rather than with the original base without special treatment of the original subject, the original subject being free of any coating 130 between the picture and the original base upon which the picture is carried, separating the original base from the fabric, bringing out the coloring on the fabric, and fixing the coloring 135 on the fabric.
